(57) **CLAIM**

The ornamental design for a tool tray for use on a step ladder, as shown and described.

DESCRIPTION

FIG. 1 is an isometric view representing a tool tray for use on a step ladder;

FIG. 2 is a top view thereof;

FIG. 3 is a bottom view thereof;

FIG. 4 is a front view thereof;

FIG. 5 is a rear view thereof; and,

FIG. 6 is a side view thereof, the opposite side being a mirror image.

The broken lines form no part of the claimed invention.
